NICOLAI MINORSKY, OF SWARTHMORE, PENNSYLVANIA

STABILIZING APPARATUS

Application filed June 15, 1931. Serial No. 544,651.

This invention relates to improvements in stabilizing apparatus for ships, submarines, airships and the like. More specifically it relates to, and has as an object to provide, a new method and means for timing the action of the stabilizing equipment in response to the combined effect of the deviation of the system to be stabilized from its normal non-disturbed position in space on the one hand, and to the angular velocity, angular acceleration and still higher time derivatives characterizing the development of the deviation in time, on the other hand. Owing to the presence of the higher time derivatives in the stabilizing control, to wit: the first time derivative being angular velocity and the second, the angular acceleration, it is possible to obtain a dead beat damping of free oscillations and to reduce considerably the amplitude of forced oscillations of the body to be stabilized, whereby a very close stabilization is obtained and the securing of these effects is included among the objects of this invention.

As a preferred embodiment of this invention I show the application of this method to antirolling stabilization of the ship by means of a moving weight shifted athwartships by a source of external power and exerting a stabilizing moment about the longitudinal axis of the ship so as to compensate for the disturbing effect of the wave slope tending to produce the rolling. It is well known that the method of shifting the weight athwartships is due to Sir J. Thornycroft who applied this means for stabilization of a yacht *Cecile* (and published his results in the Proceedings of the Institution of Naval Architects in 1893). The Thornycroft method of timing the motion of the weight was derived from the angle of deviation of the ship from its upright position obtained by means of two pendulums of which one had the short and the other the long periods. The first mentioned pendulum was following the direction of the apparent and the second of the true gravity. The Thornycroft equipment could quench only about one half of the roll owing to the inherent limitations of his equipment. To obviate the deficiency of the

Thornycroft system is among the objects of this invention.

The present invention is an improvement in and differs essentially from the Thornycroft idea in that in addition to the purely positional control responsive to the angle of deviation of the ship from its upright position, it possesses, owing to the introduction of controlling means responsive to the higher time derivatives of the disturbing angular motion, an advance of the phase of the stabilizing action whereby a more accurate stabilizing effect is obtained. This last mentioned part of control is designated in the following as dynamical and its action can be understood from the following elementary consideration: when the ship on rolling passes momentarily through its upright position, for example, from starboard to port, the angle of deviation is zero at this instant and the weight controlled from this angle, as in case of a purely positional control of the gravity stabilizing equipment, is amidships and hence exerts no stabilizing effect. Owing to the kinetic energy of rolling the ship swings further to port. In the present invention the presence of the angular velocity control will already have moved the weight to starboard so that when the ship reaches its upright position it has no, or only small, angular velocity—whereby a dead beat stabilization is obtained. Likewise the advantage of the accelerational control can be appreciated from the following: assume that initially the ship is at rest and in the vertical position and that a disturbance, such as solitary wave, for example, begins to act at a given instant. According to dynamics the angular acceleration will develop in proportion to the instantaneous value of the disturbing moment since the other effects due to buoyancy and skin friction can be neglected for the conditions assumed i. e. at the very beginning of the disturbance. Both the angle and angular velocity are small enough at this point but the angular acceleration generally is proportional to the disturbance and hence is of the first order assuming a parabolic approximation about the initial instant. An angular acceleration responsive means in this

case theoretically affords a finite controlling action whereas both the angle and the angular velocity responsive means offer actions of smaller or negligible magnitude; it offers thus a truly anticipatory action whereby the equipment is made to respond to the cause (i. e., disturbing moment) rather than to the effect, which is the developed angular motion. The accelerational control permits 10 thus to control directly the inertial properties of the system to be controlled—ship in this instance—and hence is particularly valuable in all kind of transient disturbances characterizing the actual conditions of the 15 sea.

In general, by considering any disturbance whether periodic or not as a function of time and expanding it in Taylor's series around the given point, it can be shown that the accuracy of predetermination of the controlling action by automatic equipment is the greater, the greater the number of terms of this expansion, that is the greater number of higher time derivative responsive means 20 is used for the control.

More specifically, this invention improves and has as an object to improve the timing of motion of the weight so that for the same weight a greater stabilizing action is produced owing to the exact predetermination of the controlling action, above mentioned, than in case of controlling equipment of the prior art. The influence of this novel method and means for producing an adequate timing manifests itself in the damping out of the free oscillation as well as in reducing the amplitude of the forced oscillation of the ship in a steady state of rolling among harmonic waves. However, as harmonic wave motion 30 is the exception, and non-harmonic transient wave motion is more frequently the actual condition, it will be understood that the utilization of the second and still higher time derivatives for controlling action affords true 35 and complete anticipatory action, as shown above, not obtainable with transient conditions, from angle and angular velocity control alone.

The above elementary explanation relative to the advance of the phase of controlling action obtained in this invention can be still better understood from the following theoretical explanation.

It is known that under the assumptions of the general theory of William Froude, now universally accepted in the art, the differential equation for unresisted rolling among the waves is:

$$\frac{d^2\theta}{dt^2} + b^2\theta = b^2\Theta \sin \omega t \dots \dots \quad (1)$$

where θ is the angle of the ship's masts with 65 the vertical,

Θ is the maximum angle between the normal to the wave profile and the vertical.

$$\omega = \frac{2\pi}{T}$$

where T is the apparent period of the waves. 70

$$b^2 = \frac{Wh}{A}$$

where W is the displacement of the ship. 75

A is the moment of inertia of the ship about the longitudinal axis passing through its center of gravity.

h is the metacentric height.

When a stabilizing weight w is provided on the right side of this equation a term c^2x is added representing the stabilizing moment of the weight where

$$c^2 = \frac{w}{A}$$

and x is the variable distance between the center of gravity of the moving weight w and the middle line of the ship.

By providing follow up devices either on controlling instruments and on the torque producing means or only on the latter I am able to vary the lever arm x of the weight in accordance with the following law: 90

$$x = m\theta + n\frac{d\theta}{dt} + p\frac{d^2\theta}{dt^2} \dots \dots \quad (2)$$

where θ is the instantaneous angle of rolling,

$$\frac{d\theta}{dt}$$

is the instantaneous angular velocity of rolling,

$$\frac{d^2\theta}{dt^2}$$

is the instantaneous angular acceleration of rolling and m, n, p are suitable coefficients of proportionality characterizing the intensities 110 of the component controls (1) by the angle θ , (2) by angular velocity

$$\frac{d\theta}{dt}$$

(3) by angular acceleration

$$\frac{d^2\theta}{dt^2}$$

These coefficients m, n, p can be either positive 120 or negative according to one of the two ways of connecting the corresponding control instrument.

In order to simplify the discussion, assume that $p=0$, that is, the lever arm x of the moving weight is controlled at any moment by means responsive to a linear function

$$x = m\theta + n\frac{d\theta}{dt}$$

of the angle and angular velocity. Substitution of ω into the differential equation of rolling gives:

$$5 \frac{d^2\theta}{dt^2} - c^2 n \frac{d\theta}{dt} + (b^2 - c^2 m)\theta = b^2 \Theta \sin \omega t \dots \dots (3)$$

It is well known from the nature of Equation (3) that in order to secure the damping of free oscillations the coefficient n must be negative, which means that when the angular velocity of rolling is from port to starboard, for example, the weight is moved from starboard to port and vice versa. As regards the second coefficient m there is no such definite indication; it may be either positive or negative. In the original Thornycroft equipment it was positive which means that when the angle of roll is to starboard for example the weight goes to starboard which can be designated as a "downhill" control.

Assuming for the sake of example that m is negative and designating by N , M , the absolute values of m , n , one has:

$$25 \frac{d^2\theta}{dt^2} + c^2 N \frac{d\theta}{dt} + (b^2 + c^2 M)\theta = b^2 \Theta \sin \omega t \dots \dots (4)$$

Comparing this with the original Froude's Equation (1) one notes the term

$$30 c^2 N = \frac{d\theta}{dt}$$

characterizing the presence of a damping factor of the form

$$35 e^{-\alpha N/2}$$

in the expression for the free oscillations of the ship. Furthermore the amplitude of the forced oscillations θ_1 , is also decreased as follows from the expression for the particular integral of Equation (3) corresponding to the given second member.

$$40 \theta_1 = \frac{b^2 \Theta}{\sqrt{[(b^2 + c^2 M) - \omega^2]^2 + \omega^2 c^2 N^2}} \dots \dots (5)$$

45 where θ_1 is the amplitude of forced oscillations due to wave slope.

Equation (5) shows that the amplitude of the forced oscillation is reduced owing to the term with N . The discussion can easily be extended in case the accelerational control is provided. It also can be shown that the accelerational control is equivalent to a virtual modification of the moment of inertia of the ship whereby the performance of the equipment becomes still more effective both from the standpoint of increasing the decrement of free oscillations and of the reduction of the amplitude of forced oscillations.

60 It is seen thus that the means responsive to the dynamical control accomplishes three important functions:

1. Introducing an energetic damping of free oscillations of the ship.

65 2. Reducing the amplitude of forced oscil-

lations to a much greater extent owing to the terms with N and P .

3. Exerting an early anticipatory action in cases of transient disturbances owing to the higher time derivatives.

The stabilizing means forming the subject of this invention furthermore possesses as smooth and continuous action as the primary disturbance itself, which permits of obtaining a close balance between the cause (i. e. external disturbance due to the waves) and the effect (i. e. stabilizing movement of the weight) continuously at any moment. Furthermore both the intensity and the direction of controlling actions in this invention can be varied at will to meet, on different ships, different conditions of rolling, and, for the same ship, to meet different conditions of weather, apparent period of waves and the like.

It is an important object of the invention, to provide a substantially electrostatic currentless control of the power circuits actuating the torque exerting plant whereby a continuous regulation of the character described is produced by small high precision delicate instruments responsive to angular motion, avoiding any possible interference with the accuracy of their performance owing to secondary effects of friction ponderomotive forces in the electromagnetic fields, and the like. The performance of the equipment under these conditions is reliable, subject to easy control, adjustment and accurate predetermination.

When the rolling is too heavy and is outside the range of the roll quenching capacity for which the stabilizing equipment is designed, I provide, and it is an object of the invention to provide, emergency means whereby the moving weight is brought to rest at the end of its stroke irrespective of the fact that the angular motion has not been mastered by the weight. In such a case the stabilizing equipment functions continuously within its roll quenching range and discontinuously at the end of the stroke. Finally owing to the possibility to adjust the performance to a "downhill" control a partial regeneration of energy can be secured so that the power plant moving the weight needs to supply a comparatively small amount of energy.

It is an object of the invention to provide, in connection with a rolling weight as the stabilizing agency, a transverse guiding track of such profile as to maintain a substantially constant load on the power source and to obtain a regeneration of energy owing to the conversion of the kinetic energy of the moving weight into potential energy of the same weight when raised at the ends of its stroke on the profile and vice versa. Furthermore the profile of the guiding track is such that no damage can occur to the ship in case the

stabilizing weight becomes disconnected from its power source. In determining the profile of the guiding track it is preferred to provide a track in which a comparatively small curvature is offered to the weight in the central portion of the ship when the motion of the weight is normally the fastest and gradually increasing curvature is introduced for increasing distances from the center line 10 of the ship where the kinetic energy must be finally absorbed so as to prevent the possibility of impact at the end of the stroke. All of these advantages are particularly well obtained in the case of a cycloidal track, which, 15 in addition, imparts a property of isochronism to a car running freely upon it. Conversely the last mentioned property permits of attainment of the inherent safety above referred to, as well as uniformity of the load.

20 Other important features and objects of this invention will be apparent from the following description accompanied by the following drawings in which:

Fig. 1 shows the general arrangement of 25 the stabilizing equipment,

Fig. 2 shows a detail of Fig. 1,

Fig. 3 shows the pendulum control instrument,

Fig. 4 shows a detail of Fig. 1,

30 Figs. 5 and 6 represent the angular velocity control instrument,

Fig. 9 represents the angular acceleration control circuits,

Fig. 10 represents a modification of the arrangement shown in Fig. 9,

40 Fig. 11 represents diagrammatically the performance of the arrangement shown in Fig. 10,

Fig. 12 represents a wiring diagram of a modified form of the invention particularly 45 applicable to the arrangement shown on Fig. 8,

Fig. 13 represents a modification of the instrument shown on Fig. 3, particularly adaptable to use with the arrangement shown 50 on Fig. 12,

Fig. 14 represents a modification of the instrument shown on Figs. 5 and 6, particularly adaptable to use with the arrangement shown on Fig. 12,

55 Fig. 15 represents an angular acceleration responsive instrument,

Fig. 16 represents a side elevation of a cycloidal track supporting the moving weight, and

60 Fig. 17 represents a diagrammatic detail of the electrical follow up member.

Referring to Fig. 1, the moving weight 1 is shown as a block of metal capable of rolling athwartships along a track 2 on the 65 wheels 3. The cable 4 (or plurality of cables)

causes the displacement of the weight 1 under the influence of pressure developed in the double acting hydraulic cylinder 5 whose piston rod 7 supports on both ends suitable blocks of pulleys 6 mounted to form together 70 with pulleys 10, fixed to the ship by means of the brackets 11, multiple sheave pairs of blocks with one end 8 of the cable secured to the ship's frame and the other leading end passed through additional pulleys 9 and from 75 there secured to the weight as shown.

It is known that the arrangement shown permits a displacement of the weight across the ship for a comparatively short stroke of the piston in the cylinder 5. The cylinder 80 5 is in communication by means of tubes 12 with a hydraulic variable delivery pump 13 driven by a constant speed motor 14 with a fly wheel 15 to equalize the effects of the variable load during the performance of the set. 85 The control member (sometimes designated as floating ring) 16 of the pump 13 is acted upon by regulating means forming the main subject of this invention.

It is known that for a definite angular positioning of the control 16 of the pump, indicated for the sake of example by the angle α , from its middle position shown on Fig. 1 there is a corresponding definite rate of discharge of the pump, and hence a definite 95 speed of the piston and of the moving weight. The reversal of the control member 16 around the zero point reverses the direction of the discharge and hence the direction of motion of the weight.

A slotted lever 17, pivoted around the point 18 engages a pin 20 concentric with pulley 6 as shown. Displacement of the piston rod 7 secures corresponding oscillations of the lever 17 about the point 18. By means of a system of levers 21 and 19 large displacements of the piston rod 7 secures corresponding proportionally reduced parallel displacements of the lever 19 through the pivotal connection of the latter at 22 with slotted lever 17.

A lever 23 with the pivotal point at 24, has its opposite end constrained by springs 25. A slotted lever 26 is slidably connected at the point 27 to the lever 19; the lower end of lever 26 is connected to the lower end of lever 23 by means of link 28.

At the point 29 of lever 23 there is linked a lever 30 connected at the point 31 to floating lever 32. The upper end 33 of lever 32 is pivotally mounted on the nut 34 capable of being displaced longitudinally along the screw 35 during the rotation of the latter. The shaft 35 is fixed in driving relation to the planetary system 36 of epicyclic gears, shown in detail on Fig. 4; the bevel gears 37, 38 are loose on the shaft 35 and are fixed to spur gears 39, 40 respectively, engaging corresponding spur gears 41, 42 on the shafts 125 of the motors 43, 44 provided with series 130

brakes 45, 46; from the same motors through a suitable gearing and shafting 47, 48 (Fig. 1) are actuated the shafts 49, 50, controlling the follow-up devices on the instruments 51 and 52, responsive to the angle, and angular velocity of, the rolling, respectively. The instrument 52 controls the excitation of a generator 53 driven by a motor 54; the armature of the generator 53 is connected to the 10 armature of the motor 43, by means of a cable 55, the excitation of the motor 43 is constant (not shown); the electric circuits relative to the control of generator 53, motor 43 by the instrument 52 are explained in connection 15 with Fig. 7.

The instrument 51 shown in detail on Fig. 3 is a direction indicating apparatus of long period pendulum type. It may contain gyroscopes (not shown) if necessary in order to 20 increase its period. The pendulum 56 is supported on a knife edge 57 by the arm secured to the pedestal 58 in which is fitted an arc shaped segment 59 having worm wheel teeth on its lower end with which is engaged the 25 worm 60 connected to the shaft of the motor 44. On the upper part of the segment 59 is placed an arc of insulating material 61 with two conducting segments, 62, 63, separated by a short arcuate gap 64 of the insulator, 30 which may be air.

The pendulum 56 bears on its lower end a block of insulating material 65 to which is fixed with a certain resilience the fork 66 supporting a metallic trolley wheel 67. The trolley 67 with two segments, 62, 63 controls in the well known manner a relay 68, closing the contacts 69 and 70, of the follow-up motor 41 as shown. The well known property of such a system is that the gap 64 seeks always 40 to reach the trolley 67, around which position the system oscillates or hunts slightly. When the ship rolls over a certain angle θ to the starboard (for instance) the pendulum 51 remaining fixed in space the segment 63 is 45 displaced by the same angle θ until the gap 64 reaches again the position of the trolley 67. When this is accomplished the motor 44 will have turned through a number of revolutions proportional to that angle θ as will also 50 the gear 38, loosely mounted on the shaft 35. Assume that the other gear 37 is fixed—in such a case the nut 34 will have a displacement d , along the screw 35 also proportional to the instantaneous angle of roll. This follows up action will prevail continuously 55 throughout the ship's rolling motion.

By providing suitable means (not shown) for tilting the frame of the instrument 51, shown on Fig. 3, about the long axis of the 60 ship, I am able to modify the setting of the directional instrument from the upright undisturbed position, to any other predetermined position, making a certain constant angle of deviation with the former (nondisturbed) setting. In this case the stabilizing

means described in this invention will stabilize the vessel not about its normal upright position, but about this predetermined inclined position. This is of importance in all cases where a given list must be compensated for, or an artificial list created as in the case of artificial increase in elevation of fire in naval vessels. 70

The instrument 52 is an angular velocity indicating apparatus shown in detail on Figs. 5 and 6. It contains two gyroscopes 71, 72, driven in opposite directions with their casings pivotally mounted within a frame 73 about two parallel axes A—A, B—B, placed athwartships. Four cylindrical metallic 80 tanks 74, 75, 76, 77, made of metal not attackable by mercury, are secured to the frame 73 by means of an insulating support 78. The circular bases of the tanks are made of a resilient material to form diaphragms. 85 Centralizing springs may be added if necessary in order to ensure the horizontal position of the gyroscope. The tanks are completely filled with mercury and have, on their upper parts, each one capillary glass tube 90 respectively, 79, 80, 81, and 82 in communication with the tank with a deposit of a metal nonattackable by mercury forming a high resistance film. It is known that the films of this kind may have very different values 95 of resistance per unit of their length varying from a few ohms up to several megohms depending on the thickness of the deposit; they may serve as variable resistors during the variation of height of the mercury column. The respective brackets 83, 84, 85, and 100 86 are fixed to the respective casings of the gyroscopes as shown and have the thumb screws 87, 88, 89, and 90, each having a piece of insulating material respectively, 91, 92, 93, 105 and 94 at their ends and permitting the adjustment of the initial pressure exerted from the gyroscopes on the tanks. For a given adjustment and no angular velocity of rolling the height of the mercury in the tubes 79, 80, 81 and 82, has a certain initial value in the middle of the tube. When the angular velocity of the rolling occurs, the gyroscopic reactions appear simultaneously therewith being proportional to the instantaneous value 110 of this angular velocity, one pair of tanks (76, 77, for example) is therefore compressed and the other pair (74 and 75) expanded, which causes the rise of the mercury in the capillary tubes 81, 82, and the fall of the mercury in the tubes 79, 80, in proportion to the instantaneous angular velocity of rolling and this is utilized for the purpose of control 115 shown on Fig. 7.

A constant potential difference from a battery 95 is impressed on the tubes 79, 80, 81 and 82, as shown, viz., positive terminal is connected to the tubes 79 and 81, and the negative to tubes 80 and 82. When there is no angular velocity of roll and hence no dif- 120 125 130

ference of pressure set up by the gyroscopes in the tanks the potential of the tanks 76, 75 connected together is the same as of the tanks 74, 77, connected electrically together. If, however, the gyroscopic pressures (indicated by arrows) appear, the potential of the point 96 rises above, and that of point 97 goes below, its former equal value. A resistor 98 connected across the same source of supply 95 has its middle point 99 connected to the common negative terminal of the A battery (not shown) feeding the filaments of two three electrode power tubes 100, 101 and the same point 99 being connected to the negative terminal 102 of the plate supply. The points 96, 97, on the insulated tank systems are connected to the grids of the tubes 100, 101. The plate circuits of the tubes are connected in series with differentially wound field windings 104 of the generator 53, whose armature 105 is connected to the armature 106 of the motor 43, and whose excitation (not shown) is constant. The generator 53 has another differential field 107 energized from the resistor 108 through the sliding contact 109 connected to the negative terminal 102 of the supply and displaced by the shaft 49 (Fig. 1), mechanically connected with the armature shaft of the motor 43. For the equal heights of mercury in the tubes 79, 80, 81 and 82 the grid potentials of the tubes 100, 101, are equal and the magnetomotive forces of the differential split field 104 compensate each other; if at the same time the contact 35 109 is in the middle of the resistor 108 the magnetomotive forces of the differential field 107 also compensate each other and the generator 105 is not excited in this case. If on account of the angular velocity of rolling 40 the gyroscopic reactions deform the volumes of the tanks and cause the variation of the heights of mercury in the tubes 79, 80, 81 and 82, as shown, the potential of the point 96 increases, which increases the current in the plate circuit of the tube 100 (by a similar reasoning it is seen that the plate current of the tube 101 decreases). This causes the unbalancing of the differential field 104 of the generator, and starts the armature 106 of the 45 motor 43, which runs through a number of revolutions corresponding to the displacement of the contact 109 sufficient to produce an unbalancing of the field 107 offsetting the original unbalancing of the field 104. It is seen thus that to a given value of the instantaneous angular velocity of rolling corresponds in final result a certain number of revolutions of the motor 43 from its zero value. This condition exists continuously throughout the motion and holds for the instantaneous values of angular velocity. It is fulfilled better the more rapid is the control. The control afforded by the three electrode vacuum tubes of the type disclosed affords these advantages of continuity as well

as rapidity. The last condition is readily understood from the fact that the time constant of an inductive circuit such as the field 104 is greatly reduced owing to a very high ohmic resistance of the tube inserted in series with such a circuit. I wish it to be understood that the use of the electron discharge tube circuits with the arrangement of the tanks disclosed is described by me as an example of a continuous, rapidly acting control and not in a limiting sense, since any other controlling arrangement satisfying the above stated conditions of continuity and of the absence of an appreciable time lag is equally good for this purpose. Such alternative construction 75 is illustrated in Figs. 12, 13, 14 and 15 and discussed in the description of those figures which follow later herein.

Summarizing the preceding disclosure one can state that the described arrangement has the following properties:

- To a definite value of the instantaneous angle θ of rolling there is a corresponding proportional number of revolutions of the motor 43 from its zero position, when the angle $\theta=0$, i. e. when the ship is upright.
- To a definite value of the instantaneous angular velocity

$$\frac{d\theta}{dt}$$

of rolling there is a corresponding proportional number of revolutions of the motor 43 from its zero position, when the angular velocity of rolling

$$\frac{d\theta}{dt}$$

is zero.

A definite instantaneous state of motion

$$\left(\theta, \frac{d\theta}{dt} \right)$$

is therefore represented in this invention by a proportional instantaneous displacement (d) of the nut 34 from its middle position of the type

$$d = d_\theta + d_i = m' \theta + n' \frac{d\theta}{dt}$$

where the factor of proportionality m' contains the ratios of transmission in the system controlled by the instrument 51 and the factor n' contains the ratios in the system controlled by instrument 52. The linear combination of both terms

$$d_\theta \text{ and } d_i$$

is obtained by means of epicyclic gear 36.

Having described the nature of displacement of the nut 34 under the influence of angle and angular velocity of rolling it is necessary now to describe the control of the moving weight 1 effected by means of the lever system shown on Fig. 1. The purpose of this lever system is to produce the follow-

up control of the motion of the weight, whereby the displacement x of the weight becomes proportional to that of the nut 34.

A given displacement of the nut 34, for example to the left, causes the opening of the control member 16 of the hydraulic pump 13 since the point 31 is fixed initially. A corresponding motion of the weight 1 for example to starboard is thus started checking the instantaneous roll to port. The piston rod during this phase of motion is moving to port displacing also to the left through levers 17, 19, 26, 30, the point 31 of the floating lever 32, which causes a decrease in the angularity of this lever and also decreases the angle α of the control member 16 decreasing the speed at which the weight is moving. For a definite initial displacement of the nut 34 the moving weight will be moved by the amount necessary to displace the point 31 to the left in order to bring the control member 16 back to its middle position which thus stops the weight. In reality the initial displacement of the weight causes a decrease in the angular velocity of rolling, which in its turn causes the reverse rotation of the motor 43 and the motion to the right of the nut 34. This receding motion of the nut 34 to the right, will contribute still more to the return of the control member 16 to its neutral position when the discharge of the pump and also the motion of the weight stop. Thus for a definite initial displacement of the nut 34 there is a corresponding proportional displacement of the point 31 and therefore of the weight 1, sufficient to offset the initial displacement of the nut 34 and stop the discharge of the pump by bringing the control member back to its middle position.

It may happen, however, that owing to an excessive rolling the stabilizing equipment will not be sufficient to quench it. To meet this emergency the lever 23 is provided—it is pivoted about the point 24. The lever 19 has two stops 110 and 111, capable of reaching the lever 23 for a sufficiently long excursion of the weight and hence of the lever 19. Assuming again the previous example when the weight moves to starboard and the levers 17, 19 to port, the above emergency condition will occur when the stop 111 will swing the lower end of the lever 23 to port, helping thus to bring the point 31 more rapidly to port than this would happen normally, when the point 112 is stationary. The lever 23 is therefore an emergency means and its function is to stop the weight near to the end of the track irrespective of the fact that the angular motion has not been mastered by the weight, which is manifested by a too considerable excursion of the travelling nut 34. The case when the lever 23 is acting constitutes a rather abnormal operation of the equipment during very heavy roll. The cases when the lever 23 is not working, con-

stitute the normal performance of the stabilizing equipment within its roll quenching range.

Having described various parts of this invention as set out in Figs. 1 to 11 inclusive, I wish now to describe the normal performance of the device as a whole omitting any intermediate explanations already given in the course of description of the various parts. Assume, for example, that at the initial instant after a period of a quiescence the disturbing moment of the wave slope begins to act on the ship tending to roll it to starboard. The gyroscopic reactions of the gyroscopes 71, 72, modify the level of mercury in the tubes in proportion to the instantaneous values of angular velocity of rolling and through the vacuum tube system produce the voltage in the generator 53 and start the motor 43 and also the epicyclic gear 36 from the bevel gear 37. With a slight retard the actual deviation θ of the ship to starboard will develop to the extent sufficient to start the pendulum motor 44 since, on account of rolling, the trolley contact is now on the strip 63 thus closing the relay 68, on the contact 70. The pendulum motor will be started to run through a number of revolutions proportional to the angle of the instantaneous roll and this condition will prevail continuously throughout the subsequent performance. If the angle to starboard is designated as positive, (that to port as negative), and angular velocity to starboard as positive, (that to port as negative), this initial condition of this assumed case is therefore characterized by:

$$\theta > 0 \quad \frac{d\theta}{dt} > 0 \quad \dots \dots \quad (1)$$

The connection of electrical circuits and mechanical follow up systems 47, 48, must be such that for this Period (1) of the motion the bevel gears 37, 38, be moved additively so that the displacement d of the travelling nut 34 controlling the displacement of the weight 1 is due to the sum of two partial displacements which would occur if each of the two motors 43 and 44 were working alone. The displacement of the travelling nut in this case will be therefore $d_1 = d_a + d_b$ where d_a and d_b are the partial displacements due to the angle θ control and angular velocity

$$\frac{d\theta}{dt}$$

105

110

115

120

controls respectively.

The stabilizing device during this phase (1) of the ship's oscillation consequently develops a kind of "meeting" action exaggerating the displacement of the weight as compared to what it would be if the timing were only due to the pendulum.

The weight having been moved very vigorously during this first "meeting" stage of the

angular motion will produce on the ship a counter torque thus decreasing the rate of angular motion to starboard; during this second period θ is positive and increasing 5 more and more gently:

$$\frac{d\theta}{dt}$$

is still positive but decreasing.

- 10 The gyroscopic reactions being proportional to the angular velocity of rolling, decrease accordingly, which reverses the rotation of the motor 43. This is the beginning of the "easing off" period and the epicyclic 15 gear begins to work differentially, viz. while the pendulum motor 44 is still running in the old direction (since the angle θ still increases) the angular velocity motor 43 runs in the opposite direction.
- 20 An instant later:

θ begins to decrease while still being positive (3)

$$\frac{d\theta}{dt}$$

25

reverses and gradually increases in magnitude.

During this period;

$$30 \quad \theta > 0; \frac{d\theta}{dt} < 0$$

and the partial displacement d_θ approaches zero whereas d_θ' is very strong and in the 35 opposite (to its original) direction. The epicyclic gear still works differentially but the effect of the angular velocity control through the bevel gear 37 is far more considerable than the pendulum control through the bevel gear 38.

40 The displacement of the control nut 34 is now: $d = d_\theta - d_\theta'$ with the second term considerably in excess of the first one; the displacement d is thus negative, that is to port, 45 which means that the weight is moved to starboard considerably ahead of the time when the stabilized ship during its return swing (from starboard to port) reaches the upright position. This "easing off" effect 50 manifests itself particularly in this phase of motion. When the stabilized vessel returns again to the upright position the moving weight is already displaced considerably to starboard so that the ship reaches this up- 55 right position with no, or only small, angular velocity, whereas in the original Thornycroft method for this particular instant the weight was amidships and hence no "easing off" effect was provided.

60 The introduction of angular velocity control through the bevel gear 37 thus accounts for a prompt damping out of the original free oscillation and also reduces considerably the amplitude of the forced oscillation as was set 65 forth in the above theoretical summary.

The pendulum control from the instrument 51 is introduced through the bevel gear 38 into the epicyclic gear. The coefficient m in the above formula

$$(x = m\theta + n\frac{d\theta}{dt})$$

70

introduces a proportionality between the angle θ of roll and displacement of the weight: it depends on the gear ratios in the follow 75 up and lever systems. Its choice can be best indicated by considerations of statical equilibrium: $w \cdot x = Wh\theta$ where W is the displacement of the ship: hence

$$m = \frac{Wh}{w}.$$

80

The angular velocity control is more important from the standpoint of dynamic conditions, and for the purpose of adjusting the 85 proper value of the coefficient

$$n \left(x_\theta = n \frac{d\theta}{dt} \right)$$

90

in the displacement of the weight by angular velocity I may use either the change in speed of the generator 53, by varying the excitation of the driving motor 54, or modify the plate currents by means of a variable resistor 113, or thermionic emission of the three electrode tubes 100, 101, or any other regulating means in the series of controlling means between the gyroscopes 71, 72, and the armature 106 of the motor 43. This adjustment can be best made during a test when the effect of angular velocity on the damping can be directly ascertained.

95

I wish it to be understood that the preceding description of the invention must not be construed in a limiting sense since a great 10 variety of apparently different stabilizing systems may be logically included within the scope of the appended claims.

100

Thus for example instead of a dead weight pulled by cables from a stationary hydraulic cylinder the moving weight may contain the hydraulic transmission unit comprising an electric motor, a hydraulic pump and hydraulic motor; in this case the weight of this machinery adds up to the roll quenching weight; the arrangement of levers can be inverted since some of the parts, such as control member 16 becomes moving with the weight and some others, such as the point 20 becomes a fixed point—but this reversal of functions of various members is obvious, and can easily be worked out by those skilled in the art from Fig. 1.

110

Instead of a hydraulic transmission a regular electric drive can be used. For the sake of example, an arrangement of that kind is shown on Fig. 8. The moving weight 114 contains on its upper part an electric motor 115, a generator 116 driven at a constant speed 11 13

from the motor 115 and an electric motor 117 operating at a variable voltage impressed from generator 116 and driving through a suitable gearing 118, the shaft 119 transmitting the power to two drums 120, 121 actuating the cables 122, 123 displacing the weight athwartships. In this case, the power supply for the motor 117 and for the excitation 124 of the generator must be made either by flexible conductors or by trolley contacts, or the like. On Fig. 8, I indicate by 125, 126, contacts establishing the connection between the generator field winding and the bus bars 127, 128, of excitation, whose voltage is controlled by a suitable controller 129 in response to angle and angular velocity control exactly in the same manner as before (i. e. lever 32, travelling nut 34, etc.). Still better results can be accomplished when the generator's field is controlled directly by suitable circuits having a continuity of regulation and in which the composition of individual controlling action is produced electrically as will be shown in connection with Fig. 12.

Although I have described a stabilizing system in which the stabilizing moment is produced by the displacement of the weight I wish to be understood that the invention is far more general and applicable to other means of production of stabilizing moment. For example the moving vehicles (ships, submarines, airships, airplanes, and the like) can derive their stabilizing torque from vanes (not shown) suitably positioned and regulated on the port and starboard sides of the vehicle and any regulation of these vanes (either by inclining them more or less, or offering a greater or smaller surface to the medium in which the vehicle is moving) modified the stabilizing torque in magnitude and direction: the principle of controlling the vanes or any other torque exerting member remains the same, to wit: the mechanism controlling the displacement or rotation of the vanes will either be controlled by a split field of the generator described hereinafter in connection with Fig. 12 or be controlled by the travelling nut 34 whose motion is responsive to both positional (instrument 51) and dynamical (instrument 52) elements of the angular motion to be neutralized and the actual displacement of the vanes through a system of levers introduces a follow up arrangement limiting the action of the control according to the violence of the prevailing disturbance, manifested by the magnitude of the displacement of the nut 34.

The presence of the first time derivative (i. e. angular velocity) in the control accounts for damping of the free oscillation of the ship and reduces the amplitude of the forced oscillation; but it will be shown by an analysis similar to that carried out in connection with Froude equation that the presence of

the second (and still higher) time derivatives (i. e. angular acceleration of rolling, rate of angular acceleration and so on) emphasizes still more these properties by the refinements it affords in the "meeting" and "easing off" effects in timing the action of the stabilizing agency. In cases when extreme accuracy of stabilization is needed and in all cases where the waves are not strictly harmonic (the usual transient condition) the control by angular acceleration

$$\frac{d^2\theta}{dt^2}$$

can be added to the preceding so that

$$x = m\theta + n\frac{d\theta}{dt} + p\frac{d^2\theta}{dt^2}$$

where p is a suitable coefficient of proportionality between the instantaneous displacement x of the weight (or other stabilizing means) and the angular acceleration. The described system lends itself easily to this additional refinement as shown both in Fig. 9 and in Figs. 12 and 15. On Fig. 9, the tubes 100, 101, and the differential field 104, are the same as on Fig. 7. In series with the plate circuits are inserted the primaries of two transformers 130, 131, whose secondaries are connected on one side together, and to the common negative terminal of the filament battery (not shown), heating the filaments of the tubes 132, 133, the grids of these tubes are connected to the other terminals of the secondaries of the transformers 130, 131, either directly or through a suitable amplification system. The plate circuits of tubes 132, 133, are connected to an additional differential field 134 similar to the field 104. When the plate currents in the tubes 100, 101, do not vary and consequently when the angular velocity of rolling is either zero or constant, the currents of the tubes 132, 133, are equal and the resultant effect of the differential field 134 is zero also. When the angular velocity of rolling

$$\left(\frac{d\theta}{dt} \right)$$

varies, that is when the angular acceleration

$$\left(\frac{d^2\theta}{dt^2} \right)$$

exists, the currents in the primaries of transformers 130, 131, vary in proportion to the instantaneous angular velocity of rolling and the electromotive forces induced in the secondaries of said transformers are proportional, by virtue of the law of induction, to the rate of change of the flux, that is in view of the aforesaid, are proportional to the instantaneous angular acceleration of rolling. By analogous consideration one can conclude that the resultant effect of the differential field 134 is also proportional to the instant-

stantaneous value of angular acceleration of rolling. In view of the follow up system afforded by the differential field 107 this condition is equivalent to an additional term

5

$$P \frac{d^2\theta}{dt^2}$$

in the expression of the displacement x of the moving weight.

- 10 In addition to the possibility of using various stabilizing equipments in accordance with the method and means for an adequate timing as claimed in the appended claims, I wish to be understood that the described controlling 15 means must be considered as illustrative and not in the limiting sense. Thus for example instead of the potential control of the grids of vacuum tubes by means of the deformable tanks, I can use carbon piles, or a 20 resilient variation of air gaps of magnets carrying alternating current or any other arrangement in which for a given mechanical force there is a corresponding definite value 25 of the current or of electric potential, or any other, either electrical, mechanical quantity 30 which can be used for the purpose of the control of the type described.

- As another illustration of a continuously 35 acting control responsive to the deviation and to a plurality of the higher time derivatives thereof, I refer to Fig. 12, which discloses a novel system for controlling the field of generator 116, shown on Fig. 8. The disclosed system produces a combination of controlling 40 actions, responsive to the departure of the ship from its normal position and to the plurality of higher time derivatives of angular motion, in a purely electrical manner affecting one single electrical controlling system which I describe in connection with the 45 use of hot cathode grid controlled rectifiers particularly well adapted for the purpose in view when large powers have to be controlled from high sensitivity controlling instruments.

- Referring to Fig. 12, 150 is the primary of a power transformer having iron core 151 and two secondary windings 152 and 153. 50 154, 155, 156, 157 are shown as hot cathode grid controlled rectifiers comprising each a hot cathode; a grid and a plate conventionally illustrated. For the sake of simplicity the heating source of energy for the cathodes is omitted from the illustration. The rectifiers 154, 155, form a two-wave system of rectification, and are connected in a well known manner, substantially as shown, namely, their respective anodes are connected to the terminals of the secondary 152, their respective cathodes are connected together, and connected to the middle point 158 of the load circuit which in this present case is the split field winding of a generator 116 (previously described in connection with Fig. 8) comprising the fields 161 and 162. The middle

point 163 of the secondary 152 is connected to the terminal of the field-coil 162. The circuit of the field-coil 162 is thus connected in series with rectifiers 154, 155. An exactly similar arrangement is shown in connection with the secondary 153, rectifiers 156, 157, and associated field-coil 161 of the generator 116. It is apparent that according to whether the group of rectifiers 154, 155, or the group 70 156, 157, conduct the major part of the current, either the field 162 or 161 has a predominant magnetomotive force which causes a change of the generated voltage across the brushes of the generator 116 both in magnitude and direction, which causes the displacement of 80 the moving weight as has been previously explained in connection with Figs. 1 and 8. The control of the generator field in this case is produced by suitable well known control of rectifiers by the phase shift of the voltage impressed on their grids, although any other well known method of control can equally well be employed.

Referring to the same Fig. 12, 163 and 164 are the secondaries of transformers of which 90 165, 166, are the primaries. The secondary windings are connected at their center to the cathodes of the rectifiers, whereas their extremities are connected to the grids of these rectifiers substantially as shown, namely, both ends of the secondary 163 are connected to the grids of rectifiers 154, 155, and the ends of the secondary 164 are connected to the grids of rectifiers 156, 157. The primary coils 165, 166 of the grid controlling transformers, are connected to bridges 167 and 168 formed by inductances 170, 171, 172 and 173 and capacities 182, 183, 184 and 185. In view of the fact that the two circuits associated with each bridge 167 and 168, are exactly the same, description 100 will be made only in connection with one of them, although certain features relative to the interconnections will be described later herein. Each of the bridges comprises the inductances mentioned wound on the iron cores 110 (not shown) which cores are separate for each of said inductances. On the same cores are wound coils 174, 175 and 176, 177, carrying normally a direct current from a pair of electron discharge tubes, which are illustratively 115 disclosed as three electrode vacuum tubes, 180, 181, and which are connected with the coils as follows: the plate circuit of the tube 180 is connected in series with the coils 174 of the bridge 167 and the coil 177 of the bridge 168. In a similar manner the plate circuit of the tube 181 is connected in series with the coil 175 of the bridge 167 and the coil 176 of the bridge 168, substantially as shown. The condensers or capacities 182, 183 and 184, 185, already mentioned complete the bridges as indicated. The bridges are connected in parallel and across a source of A. C. voltage between the terminals 187 and 186. The scheme thus 120 described is known in the art and repre- 130

sents the use of the electron discharge tubes to modify the saturation and hence to unbalance the inductances of the bridges in opposite directions, whereby the time phase of the voltages applied to the grids of rectifiers 154, 155, is shifted in one direction, say, advanced, whereas the corresponding time phase of the voltages applied to the grids of rectifiers 156, 157, is shifted by a substantially equal amount in the opposite direction, say, retarded, as compared to the time phase of the anode voltage impressed on the rectifier system from the transformer 150.

Under these conditions the stabilizing control forming the subject matter of this present invention may be produced by the grid control of a single pair of vacuum tubes 180 and 181, as will be described now.

For the sake of simplicity, the controlling elements are diagrammatically illustrated at the bottom of Fig. 12. Their complete description in connection with the instruments producing them, is given below in connection with Figs. 13, 14 and 15. Referring to Fig. 12, 190 represents a directional control element, whose lateral displacement (along Y axis) from a central initial position XX, is proportional to the angular deviation θ of the ship from its nondisturbed position. In a similar manner an angular deviation of the angular velocity responsive rod 192 about the center 191, from its initial position along line X_1X_1 , in the plane of the drawings, is proportional to the instantaneous angular velocity of rolling, for this purpose coils 210 and 211 mounted on rod 192, are placed within alternating magnetic fields 204 and 205 respectively, perpendicular to the plane of the drawings and acting within the areas indicated by dotted lines. Likewise an angular deviation of the angular acceleration responsive rod 193 with associated coils 212, 213 relative to the magnetic fields similarly shown by projections 206 and 207, about the center 194 from its initial position parallel to direction X_2X_2 , is also proportional to the instantaneous value of angular acceleration of rolling. Finally 199 represents a control element responsive to the magnitude of the stabilizing moment whose lateral displacement along Y-Y axis, from its central position X_3X_3 , is proportional to the displacement of the weight or other torque producing mechanism from its central position when the torque is zero.

The controlling elements 190, 199 (see Fig. 12) consist of rectangular plates, made preferably of nonmagnetic and nonconducting material, such as phenolic condensation products, wood, and the like. Two flat coils 195, 196, shown on the element 190, contain a suitable number of turns of preferably thin wire, and are placed within alternating magnetic fields perpendicular to the plane of the drawing and limited to the dotted areas 197,

198. The magnets producing these fields are not shown on Fig. 12, but are shown on Fig. 13. A substantially similar arrangement is shown in connection with the element 199, namely, coils 200, 201, and zones of perpendicular magnetic alternating fields shown by dotted lines 202, 203. All magnetic fields indicated on Fig. 12 diagrammatically, by areas within which they oscillate perpendicularly to the plane of the drawing, are excited from the common source of alternating current (not shown) and hence they are all in phase with each other. It follows therefore that electromotive forces (E. M. F.) induced in various coils 195, 196, 200, 201, 210, 211, 212, 213 are all in time phase with each other. Their amplitude changes, however, as a result of the displacements above referred to relatively to the corresponding fields. For example: when the element 190 moves to the right from its shown position, the amplitude of the electromotive force induced in the coil 195 decreases and that of the coil 196 increases, in view of the fact that the number of the flux linkages through the coil 195 decreases on account of its outward motion with respect to the field 197, while the inward motion of the coil 196 relatively to the field 198 increases the amplitude of the voltage induced in that coil as the number of flux linkages is increased accordingly. Similar relations exist, with respect to the coils 200 and 201 on the element 199 constituting an electrical follow up element equivalent in its action to the lever 30 of Fig. 1, also in the angular velocity responsive coils 210, 211, and in the angular acceleration responsive coils 212, 213, with respect to their associated alternating magnetic fields indicated by areas 204, 205, and 206, 207 respectively, within which the fields are oscillating perpendicularly to the plane of the drawing. One half of the coils on all four controlling elements are connected in series substantially as shown, for example: Coil 195 of the element 190, is connected with the coil 210 of the angular velocity responsive element, which in its turn is connected to the coil 212 of the angular acceleration responsive element, which is connected to the coil 200 of the follow up control element 199. The circuit of these four coils 195, 210, 212, 200, is connected between the cathode and the grid of the tube 180, and a suitable biasing battery 215 brings the potential of the grid of tube 180 to the desirable point of performance. A plate battery 216 or other source of potential is connected between the filaments and plates of the tubes 180 and 181. The interconnection of the coils depends on the desired type of performance to be attained by the combination of the directional and of the higher time derivative responsive controls as was mentioned on page 2 in connection with the signs of the coupling coefficients m , n and 130

p. As regards the follow up control element, its connection (e. g. coil 200) must be so connected with the remaining three coils 195, 210, 212, that it will continuously reduce the initial electromotive force, which gave rise to the movement of the weight or other stabilizing means. What is said in respect to the coils 195, 210, 212, 200, is equally applicable to the coils 196, 211, 213, 201, which have to be interconnected in a similar manner so as to control the grid of the tube 181 in a manner similar to that shown in connection with tube 180. For the sake of clarity this second set of coils 196, 211, 213, 201, controlling the tube 181, is shown to be connected in a manner analogous to the coils controlling the grid of the tube 180. Condensers 218, 217 are shunted across the output of the tubes 180, 181 to eliminate the alternating component of the plate current of these tubes working as rectifiers.

The instruments actuating the controlling members 190, 192, 193 and 199 responsive to the angle of deviation θ , angular velocity

$$25 \quad \frac{d\theta}{dt}$$

angular acceleration

$$30 \quad \frac{d^2\theta}{dt^2}$$

and to the movement of the weight will be described now.

The directional control corresponding to the element 190 of Fig. 12 is shown on Fig. 13 where 220 designates a pendulum which may contain in general gyroscopes (not shown) for the purpose of increasing its period in the well known manner.

40 The pendulum is shown to be supported by the knife edge 221 arranged for oscillation about the longitudinal axis of the ship in case of anti-rolling control. The counterweights 222 and 223 permit of adjusting the pendulousness of the pendulum. On the lower part of the pendulum is fixed an arc shaped member 190 made preferably of non-magnetic and non-conducting material such as phenolic condensation material, fiber; wood and the like. Two flat coils 195 and 196 shown also on Fig. 12, are fixed to the member 190 substantially as shown.

Alternating magnetic fields indicated in Fig. 12 by projected areas 197, 198 are shown 55 on Fig. 13 as produced by corresponding electromagnets excited by the coils 224, 225 carrying alternating currents whose connections are not shown. The connections of the coils to the outer circuit is produced by means of 60 flexible conductors 226, 227 brought out near the axis of oscillation of the pendulum so as not to impair its freedom about the axis of oscillation. The pendulum 220 must be placed preferably in the tranquil point of the 65 ship as was mentioned in connection with

Fig. 3. The performance of the pendulum is apparent from the preceding description. In fact to an angle of roll θ corresponds a relative displacement between the pendulum 220 and the electromagnets 197, 198 fixed to the 70 ship in the same manner in which in the case of Fig. 3 there appears a relative displacement between the pendulum 56 and the frame 58.

The angular velocity control described in 75 connection with member 192 of Fig. 12 is shown on Fig. 14, two gyroscopes supported inside the casings 230, 231 are mounted on trunnions 232, 233, 234, 235 inside the frame 236 substantially as shown.

The instrument is secured to the ship so that the plane containing both pivotal axes 232, 233, and 234, 235 must be perpendicular to the longitudinal axis of the ship. The gyroscopes are constrained to remain in the 85 position shown by means of springs not indicated on Fig. 14. On the casings of gyroscopes at right angles to the trunnions are mounted links 238, 239 connected pivotally to the casings on one end substantially as 90 shown and on the other connected also pivotally to the lever 192 supporting the flat coils 210, 211 already described in connection with Fig. 12. The areas within which alternating magnetic fluxes act are indicated by 95 dotted lines 204 and 205. The arrangement of the electromagnets producing these fluxes is not shown on Fig. 14 since it is substantially the same as shown on Fig. 13 and is produced by analogous means. The performance of the angular velocity responsive apparatus shown on Fig. 14 is the same as that of the corresponding instrument shown on Fig. 5. The gyroscopes are arranged to spin

in opposite directions and react on angular 100 velocity of rolling by opposite tilts about their trunnion axes transmitting to the lever 192 a rotation about a center 191 located between the points 240 and 241 where the links 238, 239 are connected to the lever 192. This 105 modifies the number of linkages between the coils and the magnetic fluxes. Thus for example when the link 238 is moved to the right and the link 239 to the left the lever 192 moves clockwise and the alternating electromotive force induced in the coil 210 increases and that of the coil 211 decreases substantially in proportion to the amount of the displacement and hence in proportion to the 110 instantaneous angular velocity of rolling.

Instead of deriving the angular acceleration control from the angular velocity control as shown on Fig. 9, I can obtain it directly by means responsive to the angular inertia of an inertial system. The arrangement of 115 this type corresponding to the member 193 with the associated coils 212, 213 and magnets 206 and 207 shown on Fig. 12 is disclosed on Fig. 15.

Referring to Fig. 15, 250 represents the 120

rim of a fly wheel rotatably mounted in a bearing 194 about an axis parallel to the longitudinal axis of the ship. The frame 252 supports the wheel by means of a bracket 253 on which the ball bearing or other pivotal member is mounted. For the purpose of relieving the pressure from the bearing and for the centralization of the instrument as will be apparent I provide two springs 254, 255, 10 supported by the upper part of the frame and fastened on their lower parts to two studs 256 and 257 fastened to the bar 193, which is keyed or splined to the wheel 250. The tension of the springs 254 and 255 is so adjusted as to exert an upward pull on the wheel substantially equal to its weight which relieves the pressure from the bearing 194, thus reducing the friction to a minimum and rendering the manifestation of the inertia phenomena more distinct. Attached to the bar 193 are two coils 212 and 213, shown also on Fig. 12, as already described. The stops 260 and 261 are fixed to the frame 252, normally evenly spaced from the upstanding 25 radial lug 263 mounted on the rim 250, and form limiting abutments for the oscillation of the wheel and therefore of the bar 193. The dash pots 270 and 271 are fixed to the frame in operative association with pistons 30 on the ends of rod 272 pivoted on the lug 273, fixed to the rim of the wheel.

The alternating current magnets 206 and 207 are shown diagrammatically by the horizontal projections in dotted lines in Fig. 15. 35 The performance of the inertia instrument can be understood as follows: The wheel constitutes an inertial system having a tendency to maintain its angular position in space. The ship executing its angular motion has a 40 tendency to rotate the wheel in view of the constraint by the springs 254 and 255. The torque of inertia which the springs apply to the wheel is equal to the moment of inertia of the wheel times its angular acceleration, 45 hence the extension of the springs from their middle position can be used as a measure of the latter and in view of the connections between the wheel and the coils is manifested electrically by variations of amplitudes of 50 electromotive force induced in coils 212 and 213, as was previously explained.

The dash pots permit of elimination of any residual relative motion between the wheel and the train, and the limiting system fixes 55 the performance at the desired point of mutual position between the coils and the electromagnets.

In Fig. 1, no mention was made as to the nature of the track, which may, within the scope of the invention, be rectilinear, but it is preferred to utilize a curvilinear track for the sake of numerous advantages which will be pointed out.

In the first place for a steady rolling among waves the power consumption in case of a cur-

vilinear track is considerably smaller. In fact in its extreme position the weight possesses a certain amount of potential energy due to the fact that it has been raised to a certain height on account of the curvature of the track, assuming of course that the residual quenched rolling is small enough.

The acceleration of the weight during its "downhill" phase of motion in this case is due mainly to the gravity component along the tangent to the track. During the deceleration the uphill motion of the weight on the track offers again an advantage of absorbing the kinetic energy in the form of potential energy available for the next swing instead of absorbing it by the brakes or similar irreversible devices.

In addition to this advantage a curvilinear track offers a considerably greater safety than the rectilinear one. If the curvature of the track is adequately chosen, the weight even being quite free on the track does not offer any danger to the ship; this happens when the proper period of the weight on the track is smaller than the period of the ship. Under these conditions the weight will follow the rolling and the dangerous synchronous motion of the weight can never develop.

Among the various possible profiles of the track, it appears that a cycloidal profile has 95 definite advantages:

1. The cycloid has a comparatively small curvature at its apex (where the motion of the weight is the fastest) and this curvature increases toward the end of the track.

2. The weight, if let free to roll on a fixed cycloidal track, represents a cycloidal pendulum having a remarkable property of isochronism (i. e. the period of the weight left free is independent of the amplitude) matching up a similar property of the ship within certain limits of rolling.

3. The period of a cycloidal pendulum is

$$T = 4\pi \sqrt{\frac{a}{g}}$$

where a is the rolling radius of the cycloid g is the acceleration of gravity.

For the above reasons a cycloidal profile of the track is particularly well suited for a 115 transverse shift of the weight during the steady rolling among waves and only requires greater power when a transient wave condition is encountered.

The choice of the ratio

$$\frac{a}{B} = \frac{\text{rolling radius of the profile}}{\text{beam}}$$

is of importance. Clearly the limit of this ratio is

$$\frac{1}{\pi}$$

when the complete cycloidal curve fits with in the ship's width. Such profile however

would be too "stiff" and would require too much power for the operation of the weight in transient conditions although in a steady state of stabilization among waves this last mentioned circumstance is of no special importance.

Fig. 16 shows a cycloidal profile generated by a rolling radius corresponding to the ratio

$$10 \quad \frac{a}{B} = \text{to } .12.$$

Thus for instance in case $B=50$ ft. this will correspond to $a=15$ ft.

Referring to Fig. 16, the rolling weight 1 is supported by the track 280, of the profile specified. The track is suitably supported on the frame of the vessel 281. The disclosed arrangement indicates that the driving power plant 282 is stationary in contrast with the movable power plant disclosed in Fig. 8, although either type may be used. The power plant comprises a motor 283, a brake 284, drum 285 on which is fastened the cable 286, or a plurality of such cables connected in parallel, with a suitable means equalizing the tension between the cables, (not shown). The cable is passed around pulleys 287, 288, and idler pulley 289, and is secured to the weight 1, by means of suitable yielding connections (not shown). A buffer 290 is suitably arranged at the end of the track. It is shown at but one end, but will be understood to be at both ends of the track. Weighted pulleys 291, 292 suitably supported from the ceiling of the compartment of the stabilizing weight have for their purpose to take up any slack in the cables that may occur. The idler pulley 289 has a coaxial pulley 294 of smaller radius, and the latter is in driving relation to a fixed pulley 295 through a cable 296. The fixed pulley 295 has a coaxial pulley 297 of small radius which latter is connected by cable 298, passing over pulleys 300 and 301, to sliding member 199 shown in the lower right hand corner of Fig. 12. The point of the double reduction of the linear displacement of the cable 286, by means of the pulleys and cables just described, is so that for a given displacement of the weight there is a corresponding proportional displacement, on a reduced scale, of the member 199, within its supporting system 302, whereby the follow up action is produced in the manner already described.

55 The armature of the motor 285 is connected to the armature of the generator 116 so as to constitute a variable voltage drive in which the speed of the motor 285, displacing the weight, varies substantially in proportion to the voltage across the terminals of the generator 116, both in magnitude and direction.

The structure of the preceding description made in connection with Figs. 12 to 17 inclusive, affords substantially similar stabilizing control as that afforded by the other figures

previously described. It possesses however the difference that instead of combining individual controlling actions into the resultant action controlling the stabilizing moment by means of mechanical elements such as epicyclic gear, lever system, shown on Fig. 1, and the like, it combines these individual controlling actions electrically by superposition of electromotive forces of the same phase but varying amplitudes and impresses the resultant electromotive force thus produced in response to the instantaneous conditions of angular motion on an electrical circuit controlling the torque producing plant in response to this resultant condition. An important practical feature of this last mentioned system lies in that it is possible to incorporate all high precision instruments such as those shown on Figs. 13, 14, 15 and 17, which may be inherently delicate, into one unit of relatively small dimensions having no contacts or other weak points which might otherwise interfere with the reliability of its performance. This unit obviates the multiplicity of amplifying units necessary with the system disclosed in Figs. 1 to 11 inclusive, and affords easier adjustment of the performance to meet any particular condition of sea. For instance referring to Fig. 13, the controlling action derived from the pendulum can be modified by sliding or displacing the electromagnets 197 and 198 perpendicularly to the plane of the paper by means of a set screw (not shown), which modified the linkages with the flux for all positions of the pendulum. Similar adjustments can easily be produced on other controlling elements shown on the lower part of Fig. 12, and shown in greater detail in Figs. 14, 15, and 17.

The operation of the last described system is as follows: Assume first that after a period of quiescence when the ship was in an upright position, a disturbance begins to act having a tendency to heel the ship, say, to starboard. As was explained any disturbance in its beginning can be approximated by a parabolic transient within a sufficiently small time interval. During this initial instant angular acceleration will develop in proportion to the instantaneous value of the disturbing torque and this will cause the displacement of the angular acceleration responsive member 193 in proportion to the magnitude and direction of this acceleration. The electromotive force induced in the coil 212 will increase in view of the fact that this coil will be moved into the field 206. As a result of this acceleration angular velocity, being time-integral of acceleration will develop in the course of time and the gyroscopes shown on Fig. 14 will incline the angular velocity responsive element 192, so that the coil 210 will be moved into the field 204 whereby the amplitude of the induced electromotive force will be increased. As a result of angular mo-

tion the initial departure of the vessel from its upright position will develop being time-integral of angular velocity. Assume further that, for this initial condition assumed, the angular acceleration responsive element 193 and angular velocity responsive element 192 are rotated clockwise and the angular deviation responsive element 190 moves to the left along YY axis. Under these conditions 5 the electromotive forces induced in coils 212, 210, 195 will be rather considerable in view of the fact that these coils will be displaced under corresponding poles 206, 204, 197 more than when in their assumed initial position 10 and will have a greater number of flux linkages with the corresponding fields than in their symmetrical position shown on Fig. 12. 15 This initial moment will be characterized analytically by the condition

20

$$\theta > 0; \dot{\theta} > 0; \ddot{\theta} > 0$$

A considerable electromotive force induced across the circuits of the coils 195, 210, 212, and 200 will be impressed on the grid of tube 25 180 and will produce a corresponding large plate current in this tube and also in coils 174 and 177 increasing the saturation in the magnetic cores of inductances 170 and 173 and hence decreasing the magnitude of these 30 inductances.

Opposite effects will occur in the coils 195, 211, 213 in which the electromotive forces will be reduced as a result of their being displaced from corresponding magnetic fields 35 198, 205, 207. The resultant voltage impressed on the grid of tube 181 will be thus reduced as well as will the corresponding plate current of this tube which will reduce the magnetomotive forces of coils 175, 176 producing magnetic saturation of the cores and will thus contribute to an increase of inductance of the inductive parts 171 and 172 of the bridges 167 and 168, which will be thus unbalanced in opposite directions as far 40 as the phase of the voltage impressed on the primaries 165 and 166 is concerned. The opposite variation of the time phase of the voltage impressed on the grids of the rectifiers 154 and 155 from the secondary 163 on one hand and of the corresponding voltage impressed on the grids of rectifiers 156, 157 from the secondary 164 on the other hand produces opposite variation of the average 45 rectified currents flowing from rectifiers 154, 155 and 156, 157 respectively. As is known this variation of outputs flowing through middle points of the secondaries 152 and 153 through the fields 161, 162 of generator 116 is in general a certain function of the phase displacement of the bridge voltages impressed 50 on the primaries 165 and 166 respectively, and by a suitable design can be made substantially proportional to this phase displacement. But the latter can be also made substantially proportional to the resultant ampli-

tude induced in the coils of the instruments shown on the lower part of Fig. 12. One can see, therefore, that by suitable design and adjustment of various characteristics of circuits and instruments the voltage induced in the generator 116 can be made any desired function of a substantially linear function of the type:

$$m\theta + n\frac{d\theta}{dt} + p\frac{d^2\theta}{dt^2}$$

where the coefficients m , n , p depend on the parameters of the individual circuits controlled by the pendulum shown on Fig. 13, by the angular velocity responsive instrument shown on Fig. 14, and by the angular acceleration responsive instrument shown on Fig. 15 respectively.

Thus initially a substantially high voltage generated in generator 116 will start the moving weight with a comparatively high acceleration characterizing thus the beginning of a very energetic "meeting" action employing the expression used in steering practice. This intense initial action will be reduced in the 85 course of time for two reasons:

First on account of the follow up member 199 actuated from the displacement of the weight as was explained in connection with Fig. 17 in such manner that the initial cause i. e. displacement of the coils 195, 210, 212 acquiring greater linkages with the corresponding fields will cause, through the instrumentality of the weight's displacement a corresponding removal of the voltage impressed on the grid of tube 180 will be somewhat reduced.

Secondly on account of the energetic initial displacement of the weight to port the angular acceleration to starboard may be not only reduced but completely checked although the angular velocity may still continue in its former direction, i. e. to starboard.

This phase of motion is characterized by the condition

$$\theta > 0; \dot{\theta} > 0; \ddot{\theta} = 0$$

which indicates the beginning of the "easing off" action as far as the accelerational control 115 is concerned. A moment later the condition will be

$$\theta > 0; \dot{\theta} > 0; \ddot{\theta} < 0$$

and the lever 193 of the accelerational control 120 will start moving anti-clockwise the voltage impressed on the grid of the tube 180 will be reduced because of the continued decrease of the voltage induced in the coil 212. The accelerational control acts thus as an early anticipator acting not on the effect (i. e. disturbing angular motion) but rather on the very cause insofar as the resultant disturbing moment, by virtue of the postulate of dy-

namics, is in phase with angular acceleration.

Another moment later the condition is

$$\theta > 0 \quad \dot{\theta} = 0 \quad \ddot{\theta} < 0$$

5 that is, angular velocity is zero but angular acceleration is already reversed. Now the angular velocity responsive element 192 is symmetrical with respect to the poles 204, 205 which still further reduces the voltage impressed on the grid of the tube 180 as compared to the "meeting" phase of its action and by operative association of bridges 167, 168 and rectifiers 154, 155, 156, 157 still more 10 reduces the initial unbalance of the generator field and thus contributes to a still further decrease of motion of the weight to port. The "easing off" period is very strong at this point. It is apparent that opposite phases of 15 control occur in the coils 196, 211, 213, 201 and the tube 181 controlled by the voltages induced in these coils.

At a still later instant the dynamical condition will be

$$25 \quad \theta = 0 \quad \dot{\theta} < 0 \quad \ddot{\theta} < 0$$

The ship reaches the verticality at this instant but the weight has been already displaced considerably to port by angular velocity and accelerational controls which have 30 been already reversed in earlier phases of the motion as studied here.

35 In case the ship rolls among regular waves the stationary condition as is known is characterized by 180° difference in phase between the angle and the acceleration controlling action, while the phase of the velocity controlling action is at 90° to them both.

Strictly harmonic conditions never exist at 40 sea where complicated transients due to the irregularity of the waves encountered (variable periods, variable lengths, irregular shapes) account for a somewhat erratic and, generally, not strictly periodic rolling. From the preceding it follows that the above analyzed conditions of stabilization hold in any 45 case as long as functions under study are continuous, which clearly is always the case. Furthermore the disclosed arrangement owing to its continuity permits in addition to the 50 above mentioned anticipatory features, to keep a close equilibrium between the cause (i. e. disturbing wave slope) and the effect (i. e. the stabilizing moment) continuously throughout the motion, whether harmonic or 55 not, whereby for the given roll quenching action a minimum weight is required as compared to devices of the prior art in which discontinuous controlling means, such as contacts, contactors and the like, were proposed.

60 For example, in case of the vessel of 10,000 tons having metacentric height about 2 feet, period of free oscillation 16 seconds and placed in a seaway of the maximum effective wave slope of 3° , the maximum variation of the disturbing moment per second is about

350,000 ft. lbs. A contactor or a similar discontinuous controlling arrangement which operates from time to time, say every few seconds or so, may fail to produce the desired balance between the cause and the effect, as above specified, by a very considerable amount especially when irregular conditions are met whence a comparatively poor efficiency of such devices in comparison with the above described method based on the principle of a continuous anticipatory action.

75 Although I have shown controlling means responsive to the first and second time derivatives of angular motion, it will be clear that still higher time derivative responsive means can easily be incorporated in the circuits controlling the grids of the tubes 180 and 181, as is apparent from the disclosure of Fig. 12. As regards attainment of still higher time derivatives it can be readily seen that, for example, a third time derivative responsive means can be produced from the second time derivative responsive means, in a substantially similar manner in which the second time derivative responsive means is produced from the first, as shown on Fig. 9, and this procedure can be continued still further.

80 85 In addition to the features disclosed the circuits between the filaments and grids of tubes 180, 181 shown on Fig. 12 may have additional functions such as limiting action by means of additional coils not shown operated from limit stops whereby a limiting action similar to that produced by the lever 23 on Fig. 1 can be produced electrically.

90 100 The preceding description relates to continuously acting controlling means adequate to neutralize the disturbing moment of the waves or other mechanical disturbance which acts also in a continuous manner. In this manner the disturbance is neutralized at any moment. However, in certain cases for the sake of simplification some component parts of the control may be arranged to function in a rather discontinuous manner without any departure from the spirit and scope of this invention. The regulation thus produced is generally represented in time by a rectangular curve instead of a continuous curve (e. g. of a sinusoidal shape). It is known, however, that any periodical discontinuous curve can be developed into Fourier series of which the fundamental harmonic approximates generally sufficiently well the average continuous regulation produced by such a discontinuous control; in many cases an approximation of this kind is sufficient for practical purposes.

105 110 115 120 125 I wish it to be understood that while in the following claims I intend to cover primarily the continuous controlling means responsive to the elements of angular motion (angle, angular velocity, angular acceleration of rolling) which are continuous, it is my intention to cover also the discontinuous con-

trolling means in the sense of the fundamental harmonic above referred to.

Fig. 10 represents an arrangement giving an example of this kind; for the sake of clarity only the modified elements of the arrangement shown on Fig. 9 are indicated on Fig. 10.

The three electrode electron discharge tubes 132, 133, instead of being connected in series with the differential field 134 of the generator 53 are connected to two coils of a polarized relay 135 short circuiting by means of metallic bridges 136, 137, suitably insulated, the two resistors 138, 139, inserted in series with the field 104 as shown. The resistors 138, 139 are also indicated on Fig. 7. The angular acceleration control afforded by the tubes 132, 133 is discontinuous in this case. In fact as long as the angular velocity is, for example, increasing and hence the angular acceleration is in the same direction the relay 135 remains closed on one side which gives a certain constant predominance to the control in one direction owing to the fact that one resistance only, for example 138, is short circuited. The control changes abruptly when the angular velocity (to which the departures of the plate currents of the tubes 100, 101, are proportional) goes through a maximum and begins to vary in the opposite direction; in this case instead of the resistor 138 the resistor 139 is short circuited. Thus while the angle and angular velocity controlling means are continuous the angular acceleration responsive means is discontinuous and its action (e. g. corresponding component displacement d_θ of the travelling nut 34) can be represented in time by a rectangular curve I shown on Fig. 11. The fundamental harmonic II of this rectangular curve is approximately equivalent to angular acceleration and can be substituted for the latter. It is apparent that any discontinuous arrangement of the same general type (e. g. utilizing relay, lost motion, back-lash, and the like) can be used in the above broad sense as claimed in the appended claims.

The term "ship" as used herein is intended to cover any vehicle or vessel movable or stationary.

In some instances certain parts of the disclosed arrangement can be omitted and some others added without any departure from the spirit of this invention.

Thus, for example, the angular velocity control may be omitted and the rate of acceleration control (i. e. control by the third time derivative of angular motion) added.

The accelerational control in this case will be still effective to eliminate transient disturbances but the damping of the free oscillations of the steady state of harmonic rolling will be mainly accomplished by the third time-derivative control as this can be shown

by the application of the so called Hurwitz criterion of stability.

The preceding disclosure is not limited, therefore, to the arrangement shown but must be understood broadly and defined rather by the spirit of the appended claims.

I claim:

1. In a stabilizing equipment for ships and the like, means responsive to a deviation of the ship from its predetermined normal position, means responsive to higher time derivatives of the disturbing deviation, and stabilizing means responsive to the combined effect of both said means.

2. In a stabilizing equipment for ships and the like, means responsive to the angular deviation of the ship from its predetermined normal position, means responsive to the angular velocity of said deviation, and stabilizing means responsive to the combined effect of both said means.

3. In a stabilizing equipment for ships and the like, means responsive to the angular deviation of the ship from its non-disturbed position, means responsive to the angular velocity with which this deviation varies, means responsive to the angular acceleration, with which said angular velocity varies, and stabilizing means responsive to the combined effect of all of said means.

4. In a stabilizing equipment for ships and the like, means responsive to a deviation of the ship from its non-disturbed position, means responsive to a plurality of successive time derivatives of said deviation, stabilizing means responsive to the combined effect of both said means, and means for varying the intensity of the controlling actions derived from the two first mentioned means.

5. In a stabilizing equipment for ships and the like, means responsive to a deviation of the ship from its non-disturbed position, means responsive to the angular velocity of said deviation, stabilizing means controlled by the combined effect of both said means, and means to vary the intensities of component controlling actions with which the two first mentioned means are combined to control the stabilizing means.

6. In a stabilizing equipment for ships and the like, means responsive to the deviation of the ship from its non-disturbed position, means responsive to the angular velocity of said deviation, means responsive to the angular acceleration of said deviation, means to vary the intensities of individual controlling actions of the above mentioned means, and means for controlling the action of the stabilizing means in response to a function of said controlling actions.

7. In a stabilizing equipment for ships and the like, means responsive to the deviation of the ship from its non-disturbed position, means responsive to the plurality of successive time derivatives of said deviation, sta-

bilizing means responsive to the combined effect of the first mentioned means, and means for varying the intensity of the stabilizing action obtained from said stabilizing means.

- 5 8. In a stabilizing equipment for ships and the like, means for varying the stabilizing moment in response to the combined effect of means individually responsive to the angle of deviation of the ship from its non-disturbed position, and of means responsive to the angular velocity of this deviation.

9. In a stabilizing equipment for ships and the like, means responsive to the angle of deviation of the ship from its predetermined

- 15 normal position, means responsive to the rate of change of said angle, means combining the actions of said angle responsive and rate of change of the angle responsive means, means responsive to the displacement of said

20 stabilizing means, and means to control the stabilizing means in response to a differential effect of said combining means and said displacement responsive means.

10. In a gravity stabilizing equipment for 25 ships and the like, means responsive to the angle of deviation of the ship from its non-disturbed position, means responsive to the angular velocity of said deviation, weight means arranged for movement, and means 30 for varying the linear displacement of the moving weight in response to the combined action of the two first mentioned means.

11. In a gravity stabilizing equipment for ships and the like, a weight to be moved, 35 means responsive to the angle of deviation of the ship from its non-disturbed position, means responsive to the angular velocity, means responsive to the angular acceleration of said deviation, and means for varying the 40 stroke of the weight in response to the combined action of the above mentioned means.

12. In a gravity stabilizing equipment for ships and the like, means responsive to the angular deviation of the ship from its non-disturbed position, means responsive to the plurality of higher time derivatives of the disturbing deviation, stabilizing means including a shiftable weight responsive to the combined effect of the first mentioned means and 50 means for neutralizing the action of the two first mentioned means when the stroke of the weight reaches a certain predetermined limiting value.

13. In a gravity stabilizing equipment for 55 ships and the like, means responsive to the angular deviation of the ship from its non-disturbed position, means responsive to the angular velocity of said deviation, stabilizing means responsive to the combined effect 60 of the two first mentioned means, and means for limiting the action of the stabilizing means when said action exceeds a certain predetermined value.

14. In a gravity stabilizing equipment for 65 ships and the like, a movable weight, and a

lever arm operatively associated therewith, means for varying the lever arm of the moving weight by means responsive to a linear function of the residual angular deviation of the ship from its upright position, means responsive to angular velocity and angular acceleration of the residual rolling, means for continuous variation of coefficients of said linear function both in magnitude and direction, and limiting means acting on the prime mover of the stabilizing equipment when said lever arm exceeds a certain predetermined value.

- 70 15. In a gravity stabilizing equipment for ships and the like, a prime mover, a moving weight displaced athwartships by the prime mover, means to control the prime mover in response to the combined action of the angle of rolling of the ship counted from its predetermined position in space, and to the angular velocity of rolling, and means to reduce the intensity of control of said prime mover in response to the displacement of said weight.

80 16. In a gravity stabilizing equipment for ships and the like, a roll quenching weight capable of being displaced athwartships, a prime mover to displace said weight, means responsive to the angle of rolling of the ship from its predetermined position, means responsive to angular velocity of rolling, means 90 responsive to angular acceleration of rolling, means combining the controlling action of the above mentioned responsive means, means responsive to the displacement of the weight and the means controlling the prime mover 100 in response to a differential effect of said combining means and said displacement responsive means.

- 95 17. In a gravity stabilizing equipment for ships and the like, a roll quenching weight, a prime mover to displace said weight athwartships, controlling means responsive to the angle of deviation of the ship from its predetermined position, controlling means responsive to the plurality of higher time derivatives of angular motion of rolling, resultant controlling means combining individual actions of said controlling means, follow up means responsive to the displacement of said weight, and differential means combining the actions of said resultant controlling means and follow up means and acting on the control member of said prime mover.

100 18. In a gravity stabilizing equipment for ships and the like, as claimed in claim 17, means responsive to excessive displacements of the moving weight and reducing the action of said differential means.

- 110 19. In a gravity stabilizing equipment for ships and the like, a roll quenching weight, means for displacing it athwartships, a power plant to displace the weight, means responsive to the angle of the rolling, means responsive to the angular velocity of rolling, follow up means operatively associated with 115

said angle and velocity responsive means, means to combine the actions of said follow up means, a control member of the power plant operated by said combined follow up means, means for exerting on said control member a differential action from a means responsive to the instantaneous position of the weight, and means to change the responsiveness of the last mentioned means when the stroke of the weight exceeds a certain predetermined value.

20. In a stabilizing equipment for ships, stabilizing means, means operatively associated with the stabilizing means for modifying its stabilizing action in response to the higher time derivatives of the disturbing deviation of the ship from a predetermined normal position.

21. In a gravity stabilizing equipment for ships and the like an active weight movable back and forth in an athwartship direction along a track, a variable voltage motor/generator set, a variable speed electric motor both mounted on the weight continuously acting controlling means for varying the excitation of the generator in response to the deviation of the ship from its upright non-disturbed position and to the plurality of higher time derivatives thereof, and mechanical means for connecting said variable speed motor for a positive drive of the weight on its track.

22. In a gravity stabilizing equipment for ships and the like an active weight movable back and forth along a track in an athwartship direction, an electric motor arranged for a positive drive of said weight on said track, a motor generator set, trolley contact connections between the ship and the circuits of said motor and motor generator, means for controlling the exciting current of the generator as a function of the deviation of the ship from its predetermined position and to the plurality of higher time derivatives of said deviation, and means for varying said exciting current in the opposite direction in response to the displacement of the weight along its track.

23. In a gravity stabilizing equipment for ships and the like an active weight movable back and forth in an athwartship direction along a track, an electric motor arranged for a positive drive of said weight along said track, a constant speed variable voltage motor generator set mounted on the weight, electrical trolley connections between the weight and the ship, a controlling equipment stationary with respect to the ship comprising a direction responsive instrument, an angular velocity responsive instrument, an angular acceleration responsive instrument, differential means for combining the response of said instruments into a continuous resultant controlling action actuating a controller regulating the generator's field, means responsive

to the displacement of the weight on its track for varying said resultant controlling action.

24. In a stabilizing equipment for ships and the like, means for exerting a stabilizing moment about the longitudinal axis of the ship, a prime mover adapted to cause variation of said moment in a continuous manner, controlling means including a long period pendulum, controlling means including a constrained gyroscope adapted to respond to rolling motion, controlling means responsive to the rate of change of said last mentioned controlling means, means combining algebraically the actions of said controlling means, follow up means responsive to the instantaneous value of said stabilizing moment, and a member controlling the operation of the prime mover responsive to the resultant action of said combining and said follow up means.

25. In a stabilizing equipment for ships and the like, a long period pendulum, follow up means associated with said pendulum, constrained gyroscopes adapted to respond to angular velocity of rolling motion of the ship, deformable tanks filled with a conducting liquid and operatively associated with said gyroscopes, capillary tubes internally coated with conducting material and operatively associated and forming a potentiometer with said tanks, electron discharge tubes and grids of which are controlled by said potentiometer, an electric generator having two differential field coils carrying plate currents of said tubes and another differential field winding the magnetizing action of which is controlled in response to revolutions of an electric motor fed by said generator and constituting a follow up control with respect to the angular velocity recording gyroscopic instrument, a differential gear combining both follow up actions algebraically, a prime mover controlling the magnitude and direction of the stabilizing torque, means responsive to the magnitude and direction of said torque cooperating with the action of an element of said differential gear to control the prime mover in response to a linear function of the instantaneous deflection and angular velocity of rolling.

26. In a gravity stabilizing equipment for ships and the like, a weight movable back and forth in an athwartship direction in a predetermined path, a variable voltage motor generator set, a variable speed constant excitation electric motor electrically connected to said generator, means operatively associating the motor and the weight in driving relation, continuously acting controlling means for varying the excitation of the generator in response to the deviation of the ship from its normal predetermined position and to a higher time derivative thereof.

27. In a stabilizing equipment for ships and the like, a vertical line indicating instru-

ment, an angular velocity indicating instrument, an angular acceleration indicating instrument, thermionic electron discharge tubes having electrostatic grid control and 5 operatively associated with the last two mentioned instruments, an electromagnetic apparatus controlled by said electron discharge tubes and a stabilizing torque producing plant controlled by said electromagnetic apparatus.

28. In a stabilizing equipment for ships and the like, a torque producing means, a power plant to actuate said means, instruments respectively responsive to deviation, 15 angular velocity, angular acceleration of rolling and to the magnitude of the stabilizing torque, electrical circuits having variable parameters, means operatively associating instantaneous responses of all of said instruments with a predetermined continuous variation of said parameters, and means for controlling said plant by said circuits in response to the variation of its parameter.

29. In a stabilizing equipment for ships 25 and the like, means responsive to a deviation of the ship from its predetermined normal position, means responsive to higher time derivatives of said deviation, means producing a continuous electrical controlling action in 30 response to said first and second mentioned means, space discharge means controlled by said electrical action and a torque producing stabilizing plant controlled by said discharge means.

35 30. In a stabilizing equipment for ships and the like, means responsive to a deviation of the ship from its predetermined position, means responsive to the angular velocity of said deviation, means responsive to the magnitude 40 of the stabilizing moment, means for producing an electrical action proportional to a function of the responses of the three first mentioned means, a space discharge tube system operatively associated with said electrical 45 action producing means, and a stabilizing plant controlled by said system.

31. In a stabilizing equipment for ships and the like, means responsive to a deviation 50 of the ship from its predetermined position, means responsive to angular velocity, means responsive to angular acceleration of said deviation, means responsive to the magnitude of stabilizing moment, means for producing an electrical controlling action proportional 55 to a function of the responses of the four first mentioned means, a space discharge tube system operatively associated with said electrical action producing means and a stabilizing plant controlled by said system.

60 32. In a stabilizing device for ships and the like, a ship to be stabilized, a stabilizing plant, an acceleration responsive means comprising an inertial non-pendulous element mounted pivotally about an axis parallel with the axis of stabilization of said ship, resil-

ient connecting means operatively associated with said ship and said element, an electrical controlling system responsive to a variation of resilience of said connecting means in response to the angular acceleration of said ship relatively to said element, and means to control said plant by said electrical system.

33. In a stabilizing equipment for ships and the like, a torque producing means, a power plant to actuate said means, instruments responsive continuously to the angular motion to be quenched and to the magnitude of the stabilizing moment, continuously acting amplifying relays responsive to said instruments and controlling said plant in response to a predetermined function of said angular motion.

34. In a stabilizing equipment for ships and the like, a guiding track of cycloidal profile in section perpendicular to the longitudinal axis of the ship, a weight guided on said track, instruments responsive to the angular motion to be quenched and to the displacement of the weight along said track, and a power plant operatively associated with the weight to move same in response to said instruments.

Signed at Philadelphia, county of Philadelphia, and State of Pennsylvania, this 12th day of June, 1931.

CERTIFICATE OF CORRECTION.

Patent No. 1,853,069.

April 12, 1932.

NICOLAI MINORSKY.

It is hereby certified that error appears in the printed specification of the above numbered patent requiring correction as follows: Page 1, at the beginning of the printed specification insert:-

This application is a continuation in part of my application Ser. No. 415,663, filed December 21, 1929.

and that the said Letters Patent should be read with this correction therein that the same may conform to the record of the case in the Patent Office.

Signed and sealed this 12th day of July, A. D. 1932.

**M. J. Moore,
Acting Commissioner of Patents.**
